UNITED STATES PATENT OFFICE.

WYMAN EATON, OF CHICAGO, ILLINOIS, AND DAVID T. CROXTON, OF CLEVELAND, OHIO; SAID EATON ASSIGNOR OF HIS ENTIRE INTEREST TO FREYN ENGINEERING COMPANY, OF CHICAGO, ILLINOIS, A CORPORATION OF MAINE.

BLAST-FURNACE CONSTRUCTION.

Application filed March 31, 1924. Serial No. 703,307.

This invention relates to a new and improved blast furnace construction and more particularly to a method of supporting skip inclines and charging bells upon blast furnaces.

Blast furnaces as now generally constructed are provided with skip inclines supported at an intermediate point by A frames and having an upper cantilever portion adjacent to the top of the furnace. This cantilever portion usually supports the charging bells. This method of supporting the bells is undesirable because of possibility of independent movement of the furnace and the bell supporting cantilever.

These independent movements may be caused by settling of the furnace or by unequal expansion of the furnace shell under irregular heat conditions. They may be caused by settlement of the skip incline support or by the expansion and contraction of the skip incline under varying heat conditions. An accurate centering of the charging bells is essential for a correct and uniform distribution of the furnace charging throughout the periphery of the furnace. It is, therefore, highly important that the charging bells move with the furnace in any displacements thereof.

In certain other types of furnace where the upper end of the skip incline is supported upon the furnace shell, the skip incline produces a side thrust upon the furnace which is undesirable.

It is an object of the present invention to provide a blast furnace construction having the skip incline and charging bells supported from the furnace in such manner as to insure maintenance of the adjustment of the bells relative to the furnace.

It is a further object to provide a construction of this character in which no side thrust is imparted to the furnace by the skip incline, and in which the skip and bell loads are applied substantially symmetrically about the furnace axis.

It is an additional object to provide a construction in which the cantilever section of the skip incline is reduced to a minimum.

Other and further objects will appear as the description proceeds.

We have illustrated a preferred embodiment of our invention in the accompanying drawings, in which—

Figure 1 is a somewhat diagrammatic elevation of the furnace with our invention applied thereto;

Figure 2 is a view of the furnace as seen from above, certain parts being broken away for the sake of clearness;

Figure 3 is a view of Figure 2 as seen from the left; and

Figure 4 is a side elevation of the structure shown in Figure 3.

Referring now to Figure 1, the furnace carries upon its top the skip and bell supporting structure 12 and also the outrigger 13. The skip incline 14 is supported from the structure 12 by means of links 15 which are pivotally connected to the skip incline 14 and structure 12. The upper cantilever portion 16 of the skip incline carries the top platform 17 upon which is supported the sheaves 18. The cable 19 operating the skip 20 passes over the sheaves 18 and down upon the opposite side of the furnace to the hoist house 21.

The bell operating rockers 22 and 23 are supported upon the upper extension 24 of the structure 12. The rockers 22 are connected to the small bell 25, as best shown in Figure 3. The rocker 23 is connected to the large bell 26. The rockers 22 are operated by cables 27 and the rocker 23 is operated by cable 28, these cables running down to the hoist house 21.

In this present construction it will be noted that the load of the skip incline is transmitted to the supporting structure 12 upon one side of the axis of the furnace, while the bell load is transmitted by structure 24 upon the opposite side of the furnace axis. The exact location of these loads may be so related as to substantially equalize the distribution of the load about the furnace axis. This equalization of the distribution is important in preventing unequal settlement of the furnace and minimizing temporary deflection under operating load conditions. It will be observed that with this construction it will be possible to run the outrigger 13 over the bells which facilitates removal or adjustment of the bells.

A further advantage of this structure lies

in the fact that the upper cantilever portion of the skip is quite short thus permitting the skip operating cable to pass over the opposite side of the furnace without necessitating an excessively heavy skip structure to prevent flexure under load. Also flexure of the skip incline will have no effect upon the bell location. Bringing these operating cables down upon the opposite side of the furnace is usually desirable because it eliminates idler pulleys and simplifies the handling of the cables.

We have shown one preferred form of construction by way of illustration only but it is to be understood that we contemplate such changes and modifications to meet varying conditions, as may come within the spirit and scope of the appended claims.

We claim:

- 20 1. In a blast furnace construction, a bell and skip incline supporting structure carried upon the upper portion of the furnace, a skip incline and furnace bells and bell operating mechanism, the skip incline being supported from one side of the supporting structure and the bell mechanism being supported upon the opposite side of the supporting structure.
- 25 2. In a blast furnace construction, a bell and skip incline supporting structure carried upon the upper portion of the furnace, a skip incline and furnace bells and bell operating mechanism, the skip incline being supported from one side of the supporting structure by means of pivoted links and

the bell mechanism being supported upon the opposite side of the supporting structure.

3. In a blast furnace construction, a bell and skip incline supporting structure carried upon the upper portion of the furnace, a skip incline and furnace bells and bell operating mechanism, the skip incline being supported from one side of the supporting structure by means of pivoted links, skip operating cables extending over sheaves carried by the top of the skip incline, the cables extending downwardly upon the opposite side of the furnace, and the bell mechanism being supported upon the opposite side of the supporting structure.

4. In a blast furnace, a skip incline, furnace charging bells and bell operating mechanism, a bell and skip incline supporting structure carried upon the upper portion of the furnace, the skip incline being supported upon one side of the supporting structure, skip operating cables extending over sheaves at the top of the furnace and downwardly upon the opposite side of the furnace to the skip incline, and the bell operating mechanism and bells being supported by the opposite side of the supporting structure.

Signed at Chicago, Ill., this 18 day of 65 March, 1924.

WYMAN EATON.
